PAPER CLIP HOLDER

Curt E. Nyberg, 760D Main St., Antioch, Ill.

Filed Jan. 15, 1963, Ser. No. 73,184

Term of patent 14 years

(Cl. D74—1)

FIG. 1 is a perspective view of a paper clip holder showing my new design;

FIG. 2 is an enlarged side elevational view thereof;

FIG. 3 is a top plan view;

FIG. 4 is an elevational view as seen from the left of FIG. 2; and

FIG. 5 is an elevational view as seen from the right of FIG. 2.

I claim:

The ornamental design for a paper clip holder, as shown.
